HIGHWAY AND STREET TRAFFIC MARKING
AND METHOD AND APPARATUS FOR MAK-
ING SAME

Walter A. Phillips, Salinas, Calif.

Application January 24, 1945, Serial No. 574,386

6 Claims. (Cl. 94—1.5)

1

This invention relates to the marking of highways or streets with traffic controlling markings or signs, and more particularly and specifically to the traffic marker or sign itself and the method and apparatus for applying it to the highway or street.

For brevity in description the word highway hereinafter is to be interpreted as including streets or roads, and the work markings or marker is to include signs, lines or any indicia utilized for the direction and control of traffic.

Heretofore it has been common practice to paint markers on the highway or to apply metallic or glass inserts to the highway. Paint has the disadvantage of being tracked before it becomes thoroughly dry and the necessity of blocking off a portion of the highway, after the paint is applied, until it has dried. Additionally the maintenance cost of paint traffic markers is high because of the necessity of frequent replacement. Metal inserts are objectionably costly and tend to work loose under traffic and in the majority of instances are of poor visibility in daylight hours and particularly so at night. Their raised surfaces above the highway are likewise objectionable. Glass markers are also objectionable for many reasons among which is that of breakage which causes high maintenance costs.

The present invention overcomes the objections and deficiencies of highway markers as now commonly made and used and has as an object the provision of a marker of high visibility both during daylight and night hours and one which is permanent and therefore has a negligible maintenance cost.

A further object of the invention is the provision of a novel method and apparatus for applying the marker to an already completed highway or to a highway as it is being made or laid.

Another object of the invention is the provision of a marker composed of a new material which is extremely cheap yet at the same time will withstand heavy traffic wear and at all times be highly visible.

Other objects, novel features of construction and improved results which are obtained from the marker and the practice of the invention will appear in more detail from the following description when read in the light of the accompanying drawings which illustrate one embodiment of the marker and the method and apparatus for applying the marker to a highway.

In the drawings:

Fig. 1 is a diagrammatic illustration of the

2

junction of two highways to one of which is applied the marker of the present invention.

Fig. 2 is a plan view of the mat utilized in practicing the method of the present invention.

Fig. 3 is a vertical sectional view on the line 3—3 of Fig. 2 looking in the direction indicated by arrows.

Fig. 4 is a diagrammatic view similar to Fig. 1, illustrating one step in the process of the invention.

Fig. 5 is a diagrammatic view illustrating one of the steps of the process.

The traffic marker or sign is composed of dolomite pebbles which are embedded in the highway and have only their upper ends visible. The upper ends of the pebbles are flush or substantially flush with the top surface of the highway and are arranged in a form either to constitute a word or words or some other traffic control indication such as a line down the center of the highway which is a traffic marking commonly used for dividing traffic traveling over the highway. Dolomite can be easily obtained and is particularly cheap when only in pebble sizes. This material is very white and sufficiently hard so that it will show practically no wear even under the heaviest traffic conditions. The white dolomite marking will be highly visible and particularly so if the highway is of a contrasting darker color or is made of a darker color at that area immediately surrounding the marker. The nature of dolomite is such that at night it will tend to reflect vehicle lights or gleam when struck by light rays. This material possesses a shiny substance which makes it highly desirable as a highway marking material.

In the drawings the highway marking is illustrated as comprising the word "Stop" positioned adjacent the intersection of a pair of highways and the drawings specifically illustrate the manner of applying the marking to an already paved or completed highway, and this method will be first described and thereafter the method of applying the marking to a new highway, that is a highway at the time it is laid, will be described.

Having reference now to the drawings and utilizing like characters and reference numerals 50 to designate similar parts and referring first to Figs. 2 and 3 of the drawings, E is a mat which in this instance is of a rectangular shape but its shape of course would depend upon the particular mark or word to be applied to the highway. 55 The mat is composed of some suitable compressi-

ble material. What is commonly referred to as fiberboard has been found to be a suitable material but there are innumerable compressible materials out of which a mat could be constructed. The mat is provided with a plurality of perforations 10 which are positioned in respect to one another to form the particular word or marking desired, in this instance the word "Stop." These perforations are illustrated as being of circular form but it is to be understood that they could be square, rectangular, ovate or of any form found desirable. Actually, although not preferably, a single perforation could be used for each letter of the word so that the mat would in such a case be generally similar to a stencil. A dolomite pebble 5 is positioned in each mat perforation. Filling the perforations will be facilitated by placing on the bottom of the mat a sheet of paper 3 or some other like frangible material which will close the lower ends of the holes or perforations. For simplicity in application a single sheet 3 is illustrated but of course an individual piece of material could be utilized for each hole without departing from the spirit of the invention. After each perforation has been filled with a pebble a similar frangible sheet 2 is applied to the top of the mat to seal the upper ends of the perforations. These sheets retain the pebbles in place and permit the mat to be handled and transported without danger of displacement of the pebbles.

Figs. 4 and 5 illustrate the method of applying the marker to the highway. The old or already laid pavement or roadbed is designated F and to this at the point where the marker is to be applied a sheet or coating of asphalt, bitulastic cement or black top is applied for a limited area the extent of which would be of course dependent upon the size of the marking. This asphalt or similar material is designated D and preferably, although not necessarily, would be black or of some dark color so as to make the white dolomite marking strongly contrast therewith so as to be more strikingly visible. This asphalt sheet is rolled smooth and to a suitable thickness. The thickness or depth would be dependent largely upon the particular size of dolomite pebbles being used for the reason that each pebble is to be completely embedded in the asphalt. A depth slightly greater than the thickness of the mat has been found to be highly satisfactory.

The asphalt is preferably smoothed out by a quite heavy roller which both compresses it and smooths it out. While this asphalt or plastic is still soft the mat is laid upon it as illustrated in Figs. 4 and 5 of the drawings. When the mat is properly in place pressure is applied to the top of the mat by means of a roller the weight of which can be comparatively small. It has been found desirable that this roller exert a pressure of from four to ten pounds per square inch. As the roller is moved over the mat the dolomite pebbles are forced into the soft asphalt or plastic sheet in the manner illustrated in Fig. 5 and which will now be explained. As the roller G moves over the mat the mat is compressed and as the roller reaches the mat perforations 10 the upper ends of the dolomite pebbles 5 are engaged and pushed downwardly through the mat holes or perforations. As the pebbles move downwardly the frangible sheet 3 on the bottom of the mat is broken as at 6 and due to the stretch exerted by reason of the compression of the mat the frangible sheet 2 on the top of the mat is likewise broken as at 6 at each mat perforation.

The movement of the roller G over the mat sets all of the dolomite pebbles in the asphalt sheet D and they adhere therein sufficiently to permit the removal of the mat. After the removal of the mat the asphalt sheet D with the pebbles set therein is rolled by a regular street roller which has a weight which will apply probably as great as 200 to 400 pounds per square inch. This rolling will embed the pebbles in the asphalt until the upper ends thereof are flush or substantially flush with the top surface of the strip D.

To prevent the mat from sticking or adhering to the asphalt strip which would make its removal more difficult, it has been found desirable, but not essential, to wet the mat before its application to the asphalt. As the pressure applied to the mat is only great enough to compress the mat and properly embed the pebbles in the asphalt strip the mat itself is never forced into or embedded in the asphalt. The weight of the roller used is not sufficient to cause this.

In Fig. 1 of the drawings the completed road traffic marking of the invention as applied to the highway by the process is illustrated. Here the word "Stop" is shown applied adjacent the corner of highway A at its junction or crossing with highway B. The marking is designated C and is embedded in the asphalt or similar strip D.

Where it is desired to apply marking to an old or already paved or laid street the method is slightly altered but is so similar to the method already described as to make illustration of it unnecessary. A word description will suffice to an understanding of this slightly modified method.

Where a highway is being constructed with any kind of asphaltic surface or of concrete the mat carrying the marking is applied to the highway just prior to the final completion thereof. After the highway has been rolled or otherwise smoothed the mat is applied to the top surface thereof at the particular spot or point where it is desired that the marking appear. The mat is then rolled with a light roller as has been previously described and the dolomite pebbles are forced out of the mat into the highway to a depth which is a portion of the length of the pebbles. The mat is then removed and a heavy highway or street roller is then passed back and forth over the pebbles so as to embed them completely in the highway so that their upper ends are flush or substantially flush with the upper face of the highway.

With both methods the material in which the pebbles is embedded is permitted to harden. This is of course in accord with common practice as a highway is never opened for use until all of its surface is completely hardened or set.

Utilizing the principle of the present invention highway markings of any kind can be applied at or over any desired area of a highway. A line down the center or sides of a highway could be applied with equal facility. In applying lines a plurality of strip-like mats could be utilized. The nature of the mat would of course depend upon the particular marking to be applied to the highway.

A highway traffic marking of the nature of the present invention and applied in accord with the present method provides a marker which is cheap both as to material cost and application and has the highly desirable and essential attribute of permanency and good visibility.

Departures can be made from the specific con-

structions and instrumentalities illustrated and described without departing from the inventive concept and the invention is to be limited only within the scope of the hereinafter following claims.

I claim:

1. In a device for use in applying a traffic control marking to the soft upper surface of a highway, a carrier composed of a compressible material provided with a series of spaced openings extending entirely through the carrier and arranged to depict the desired traffic control marking, an individual hard element in and substantially filling each of said carrier openings, and a frangible sheet closing the ends of said openings for retaining said elements therein.

2. An article of manufacture as defined in claim 1 wherein, said hard elements are dolomite pebbles.

3. The method of producing a traffic control marker in a highway having a plastic upper surface which hardens when set comprising, placing on the surface of a highway while the same is soft before it is set a compressible carrier having therein a plurality of individual openings extending through the carrier from the top to the bottom thereof and sealed at their ends with a frangible sheet with said openings arranged so that they form the particular highway marking it is desired to produce, and carrying in each carrier opening a dolomite pebble of a size to substantially fill the opening, passing a roller over the top of the carrier to compress the same and engage the upper ends of the pebbles and force them out of the openings past the frangible seal at the lower ends of the openings and into adhesive retention engagement with the highway, removing the carrier from the highway and from about the pebbles, then rolling the highway to force the pebbles downwardly therewith until their top ends are substantially flush with the top surface of the highway, and finally, allowing the highway to set.

4. In a device for use in applying a traffic control marking to the soft upper surface of a highway, a carrier composed of a compressible material provided with a series of spaced openings extending entirely through the carrier and arranged to depict the desired traffic control marking, an individual hard element in each of said carrier openings, means retaining said elements in said openings, and said element retaining means permitting the passage of said elements downwardly and outwardly from the openings upon the compression of the carrier by the application of pressure to the upper surface thereof.

5. The method of producing a traffic control marker in a highway having a plastic upper surface which hardens when set comprising, placing on the surface of a highway while the same is soft before it is set a compressible carrier having

therein a plurality of individual openings arranged so that they form the particular highway marking it is desired to produce and each opening carrying an element retained therein by

5 means which releases the elements upon the compression of the carrier by the application of pressure to its upper surface, applying weight to the upper surface of the carrier to compress the same to force the elements out of the openings and into adhesive retention engagement with the highway, removing the carrier from the highway and from about the elements, then applying pressure to the elements to force the same downwardly into the highway until their top ends are substantially flush with the top surface of the highway, and finally, allowing the highway to set.

10 6. The method of producing a traffic control marker in a highway having a plastic upper surface which hardens when set comprising, placing on the surface of the highway while the same is soft before it is set a compressible carrier having therein a plurality of individual openings extending through the carrier from the top to the bottom thereof and sealed at their ends with a frangible sheet with said openings arranged so that they form the particular highway marking it is desired to produce and carrying in each carrier opening an element of a length substantially the length of the opening, passing a weight over the top of the carrier to compress the same and engage the upper ends of the elements and force them out of the openings past the frangible seal at the lower ends of the openings and into adhesive retention engagement with the highway, removing the carrier from the highway and from about the elements, then applying weight to the elements to force them downwardly into the highway until their top ends are substantially flush with the top surface of the highway, and finally, allowing the highway to set.
